MAIL AND PACKAGE SORTING AND DIS-
TRIBUTING DEVICEMelvin E. Ross and Alarie L. Maynard, Los
Angeles, Calif.

Application November 6, 1935, Serial No. 48,593

2 Claims. (Cl. 211—10)

The present invention relates broadly to improvements in mail and package sorting and distributing devices, and has particular reference to an improved portable package distributing device, capable of being utilized for handling, sorting, and storing mail, mail bags, packages or the like articles to be transported from place to place.

The principal object of the invention is to provide a portable package or mail sorting and distributing device of the class described that embodies a plurality of sorting and distributing racks upon which mail or like packages may be placed, sorted and moved about the floor of any establishment and finally distributed to any carrier to which the load may be consigned.

Another object of the invention is to provide a simple, durable, and easily portable device of the class designated that, due to its style of construction, eliminates rehandling of the packages or mail bags, thus saving time in the handling of such articles and also preventing breakage of the same.

A still further object of the invention is to provide a portable package sorting and distributing device that is especially suitable for use in stock rooms, store houses and like places where packages or mail is handled in large quantities.

An additional object of the invention is the provision of a portable device of this character that may be utilized as a filing cabinet for various types of articles.

Supplementary to the foregoing objects is that of providing a portable device of the character set forth that embodies a plurality of diagonally disposed shelves or racks having means positioned thereon for holding the articles to be sorted and means for releasing said articles after they have been sorted and classified for delivery.

Other objects and advantages will be apparent during the course of the following description.

In the accompanying drawing forming a part of this specification and in which like numerals are employed to designate like parts throughout the same,

Fig. 1 is a front elevation of our improved device,

Fig. 2 is a side elevation of the same with portions broken away to disclose the construction of the portable frame, angularly disposed shelves and the means for actuating said shelves to release the packages or mail bags therefrom,

Fig. 3 is an enlarged sectional detail illustrating the construction of a section of the portable frame including one of the angularly disposed

shelves or racks, the means for holding packages or bags thereon, and the means for simultaneously actuating said shelves or racks, the section being indicated by the line 3—3 in Fig. 1, and

Fig. 4 is an enlarged front elevation illustrating the construction of one of said racks or shelves relative to the portable frame.

The invention as described resides primarily in a portable frame for handling packages or like articles and consists of a rectangular system of 10 piping embodying upright frontal and rear standards 5 and 6, respectively, preferably constructed of a plurality of pipes and T's as disclosed in Figs. 1 and 2. This frame is mounted upon casters 7 so that the entire frame may be transported 15 from place to place as a unit. This frame also includes a plurality of shelves or racks arranged diagonally, as shown in Fig. 2, and comprising flat plates 9 having frontal extensions 10 upon which indicia are placed to designate the articles upon the shelves of the device. These shelves extend diagonally from the front uprights to the rear uprights 6 and are connected to cross pieces 11 forming part of the frame.

The frontal pipe sections 12 of the frame are 25 rotatable in the T's 13 and said frontal pipe sections are provided with hook elements 14 so that said pipe sections may be rotated in said T's 13 by means of a connecting rod as herein-after set forth.

The hook elements extend through the pipe sections 12 and are provided on their inner ends with spring clips 15, said clips 15 being adapted to retain mail bags or any other packages as hereintofore described.

It will thus be observed that mail packages or any other articles may be applied to the hooks 14 and to the spring clips 15, and that when mail bags or like articles are attached to said clips 15 and the hooks 14 the hooks 14 and clips 15 40 may be rotated, thus releasing packages or mail bags deposited upon the shelves or racks of the device.

The frontal pipes 12 of the device are actuated in unison by means of a connecting rod 16 and 45 by means of actuating arms 17, as clearly disclosed in Fig. 3.

The clips 15 hold the bags in place upon the racks for the reason that the weight of the bags on the hooks 14 is overcome by the bar 16 50 which would be up in locking position flush against the horizontal bars 12 at the time that the said hooks and clips are in the positions shown in the drawing. That is, the weight of the sacks and their contents would be supported 55

mainly by the shelves 9 and would not therefore pull on the hooks 14 to any appreciable extent which are used mainly to hold the sacks open and in filling position.

5 In this manner it will be observed that any and all packages or mail bags may be simultaneously released from the spring clips 15 and the hooks 14, which clips are positioned or placed upon the shelves or racks 9 of the device due to the inclination of said racks or shelves in the frame.

It will further be observed that the hooks 14 may be utilized for the purpose of hanging mail bags, or the like, in position while being filled 15 for filing upon the shelves or racks.

Now it will be noted that if bags or packages are positioned upon said racks or shelves 9 and it is desired to transport these bags or packages from one place to the other in an establishment, 20 it is apparent that the same may be released by the actuation of the connecting rod 16 to cause the actuation or tilting of the hooks and clips relative to the shelves or racks, thereby allowing the mail bags or packages to slide from the 25 shelves or racks as set forth.

It is to be understood that the form of our device herewith shown and described is to be taken as a preferred example of the same and that various changes relative to the material, 30 size, shape and arrangement of parts may be resorted to without departing from the spirit of

the invention or the scope of the subjoined claims.

Having thus described our invention, we claim:—

1. In a device of the class described, a portable 5 frame having a plurality of article supporting racks arranged diagonally therein, means for retaining articles on said racks, said means comprising a plurality of clips having their free ends normally engaging the racks, rotatable elements carried by the frame and secured to said clips, and actuating means connected to all of 10 said rotatable elements whereby said clips are simultaneously actuated to release the gripped articles on said racks. 15

2. In a device of the class described, a portable frame including a plurality of article sorting and classifying racks arranged diagonally therein, the frontal supports of said frame being rotatable relative to the racks and the rear sections of said frame being fixed to support the rear ends of the racks, article retaining clips carried by said frontal supports, means connected with said frontal supports to cause their simultaneous rotation to release articles from 20 said clips, said means embodying operating arms connected to said rotatable elements, and an operating rod connecting all of said operating arms to cause their simultaneous actuation. 25
